METHOD OF MAKING CUSHION SOLES

James C. Givren, Brockton, Mass.

Application November 10, 1937, Serial No. 173,805

6 Claims. (Cl. 12—146)

This invention relates to cushion sole shoes and comprises more especially a novel process of making cushion soles. An important field of use of the invention is in the manufacture of welt shoes and for purposes of illustration the invention will be described in its adaptation to this particular branch of shoemaking although it is not so limited.

My invention contemplates the provision of a cushion insole presenting a continuous, unbroken grain surface beneath the foot of the wearer and having a substantial portion of its forepart, or of any other selected area, constructed to provide a soft and flexible cushion. To this end an important feature of the invention consists in forming an internal recess in the sole blank which is bottomed by a thin layer in the blank, and then enlarging the boundaries of the recess to increase its size and finally filling the recess so provided with a cushion pad. It is believed that never before in shoemaking has a recess been formed in this manner, and it offers numerous advantages. For example, the novel recess may be formed initially by a gouging operation carried out by commercial machinery available for the purpose, and then the boundaries of the recess may be progressively enlarged by a channeling operation and the material turned up to form an insole rib. The original gouging operation may be performed rapidly and accurately by employing a matrix splitting machine and the subsequent enlarging operation effected by merely submitting the recessed sole blank to an operation corresponding to that which would be performed in the regular routine of channeling the sole to provide a welt rib. By the procedure above outlined, it is thus possible to provide an insole having a recess in its flesh surface of any desired area and location covered or bottomed by a thin, continuous grain layer. The operations involved in thus fitting the novel sole are those well understood and easily carried out by the shoemaker in stock-fitting so that the insole comes to the bottoming room ready for use in regular routine of manufacture.

These and other features of the invention will be best understood and appreciated from the following description of a preferred embodiment thereof, selected for purposes of illustration and shown in the accompanying drawings in which,

Fig. 1 is a cross-sectional view on a small scale illustrating the gouging operation,

Fig. 2 is a view in perspective showing the forepart of a gouged insole,

Fig. 3 is a similar view in perspective sug-

gestive of the operation of enlarging the boundaries of the recess,

Fig. 4 is a fragmentary view in perspective of the forepart of the finished insole,

Fig. 5 is a view in perspective of the forepart of a shoe having the improved insole incorporated therein, and

Fig. 6 is a fragmentary view showing a portion of an insole cover which may be employed if desired as an optional feature.

Insole blanks are purchased by the manufacturer in assorted sizes died out to shape. As herein shown an insole blank 10 of solid leather is first presented to a matrix roll splitting machine which includes a stationary splitting knife 15, a matrix roll 11 and a flexible feed roll 12. In passing between these rolls a predetermined area of the forepart is displaced by the matrix projection into the plane of the splitting knife 9, thus removing a chip 13 from the forepart of 20 the insole, leaving it with a marginal portion 14 of full thickness and a recess having an inclined marginal wall and a bottom portion 15 of reduced uniform thickness. Preferably the sole blank is presented to the splitting machine so 25 that the chip 13 is removed from the flesh side and the bottom or cover layer 15 which remains is the grain portion of the insole. In Fig. 1 the recess is shown as symmetrically located in the forepart of the insole, but it will be understood 30 that its location and dimensions may readily be controlled by the design of the matrix roll and the manner in which the insole blank is presented thereto.

In Fig. 3 the step of enlarging the recess is 35 suggested. For this purpose a commercial channeling machine may be employed having an inside channel knife 16 and an outside channel knife 18. These knives are associated with suitable supporting and feeding means by which the 40 sole is properly gauged, presented and advanced to the action of the knives. The inside channel knife 16 has a flat cutting blade and an upstanding shank. In presenting the recessed insole 10 to this machine the blade of the inside channel 45 knife is located substantially flush or slightly above the surface of the bottom layer 15 and as the sole is advanced the surface of the layer 15 is extended progressively outwardly in the margin 14, and at the same time a slit is formed 50 which extends inwardly from the marginal edge of the blank.

The next step consists in turning up or raising the inside channel lip 17 and the outside channel lip 19 thus formed. These two lips as shown 55

in Fig. 4 are turned into upright position and cemented together to form an upstanding marginal rib which extends rearwardly in the insole somewhat beyond the heel breast line and is utilized in the manufacture of welt shoes as will be fully understood.

In Fig. 5 the recessed insole 10 is shown as incorporated in a lasted shoe having an upper 25. The welt strip 22 is sewn with the margin of 10 the upper to the rib 17-19 by the welt seam 23. The recess formed within the welt rib and 15 having the thin bottom 15 is now filled with a cushion pad 21 of such shape and thickness as to completely fill the recess, and, if desired, to project slightly above the level of the rib 17-19. Any soft, resilient material may be employed 20 for the cushion pad, although I prefer to use a blank die from a sheet of sponge rubber and cemented to the bottom layer 15. The pad 21 herein shown terminates slightly in the rear of the ball line of the shoe, but may be extended further into the shank if desired.

In Fig. 6 I have shown the forepart of the shoe bottom as including a cover sheet 24 of thin rubber which is secured at its marginal 25 edges to the outer face of the welt 22 and extends continuously across the edges of the rib 17-19 and the cushion pad 21. The purpose of the cover sheet 24 is to render the bottom of the shoe waterproof and also to give the shoe 30 a ventilating action in wear. For this purpose the thin bottom layer 15 of the insole may be provided with perforations 20. Consequently, when pressure is exerted upon the pad 21, air 35 is expelled from the perforations 20 and when pressure is released, air is drawn into the shoe bottom thus maintaining a desirable circulation of air thereto.

From the foregoing description it will be seen 40 that I have provided an improved cushion sole by a method involving only the routine operations of shoemaking. Moreover, I utilize the usual channeling operation for a double function, not only for cutting the lip required for 45 the insole rib, but for enlarging the recess of the insole and increasing the area of the thin spot and of the thin flexible grain layer covering the cushion in the finished shoe. While the rib herein shown as formed by turning up the 50 inside channel lip is characteristic of a welt shoe, it will be understood that any sole may be recessed in accordance with my invention by the two related steps of first removing a gouged chip and then progressively enlarging the bound- 55 aries of the gouged area.

Having thus disclosed my invention and described a preferred embodiment thereof what I claim as new and desire to secure by Letters Patent is:

1. The method of making cushion soles which 5 consists of reducing the forepart of a sole blank to form an internal recess of substantial area bottomed by a thin layer in the blank, broadening said recess by raising a marginal zone about the boundary of the recess to form a 10 peripheral rib, thereby providing an enlarged recess adapted to receive a cushion pad.

2. The method of making welt insoles, which 15 consists in recessing the flesh face of an insole blank leaving a thin grain layer in the blank coextensive with the recess, broadening the recess by raising a lip in a marginal zone about its periphery, turning outwardly a peripheral lip about the margin of the insole blank, uniting 20 said lips to form an insole rib, said enlarged recess being adapted to receive a cushion filler.

3. The method of making cushion insoles, 25 which consists in removing a flat chip from one face of an insole blank to form a recess of substantial area with a thin bottom, and then progressively broadening the recess by channelling outwardly from the free space of the recess, raising the lip thus formed, turning up a second lip from the margin of the insole blank, and 30 uniting said lips to form a sewing rib.

4. The method of making recessed soles, which 35 is characterized by the steps of removing a flat chip from one face of a sole blank to form a recess of substantial area, and then progressively broadening the recess and raising the lip so cut to form an upstanding sewing rib.

5. The method of making recessed soles, characterized by the steps of removing a flat chip from one face of a sole blank to form a recess 40 of substantial size, laterally slitting the inner wall of the recess at substantially the level of the bottom of the recess, and moving away the marginal material about the recess thus broadening the recess while maintaining its bottom substantially in one plane.

6. The method of making welt insoles, which 45 consists in gouging the flesh face of an insole blank to form a recess of substantial area bounded by a wide marginal wall, and then progressively channeling and turning the material 50 in both sides of said wall, thus simultaneously broadening the recess and forming the lips of an insole rib.
